DESIGN FOR AN AIRPLANE

Clifford Brandrup, Webster City, Iowa

Application June 13, 1938, Serial No. 77,809

Term of patent 7 years

To all whom it may concern:

Be it known that I, Clifford Brandrup, a citizen of the United States, resident of Webster City, Hamilton County, Iowa, have invented a new, original, and ornamental Design for an Airplane, of which the following is a specification, reference being had to the accompanying drawings, forming a part thereof.

Fig. 1 is a top plan view of an airplane showing my new design.

Fig. 2 is a side elevational view of my airplane

and Fig. 3 is a front elevational view of the same.

Fig. 4 is a bottom plan view of an airplane showing my new design and Fig. 5 is a side sectional view of the same taken on line 5—5 of Fig. 4.

Both sides of the airplane are identical in design and Fig. 2 illustrates one side thereof.

I claim:

The ornamental design for an airplane, substantially as shown and described.

CLIFFORD BRANDRUP.
